US00D646583S

(12) **United States Design Patent**
Mongeon et al.

(10) **Patent No.:** **US D646,583 S**
(b4) **Date of Patent:** **** Oct. 11, 2011**

(54) **DISPENSER**

(75) Inventors: **Murphy Greene Mongeon**, Baltimore, MD (US); **Ian Andrew Carnduff**, New York, NY (US); **Akina Kurihara**, Brooklyn, NY (US)

(73) Assignee: **The Procter & Gamble Company**, Cincinnati, OH (US)

(**) Term: **14 Years**

(21) Appl. No.: **29/364,917**

(22) Filed: **Jun. 30, 2010**

(51) LOC (9) Cl. **09-01**

(52) U.S. Cl. **D9/689**

(58) Field of Classification Search D9/682–694, D9/500–505, 516–575, 434–436, 445, 447–450, D9/454; 222/29, 135, 153.01, 153.03, 153.04, 222/153.09, 153.11–153.14, 182, 631, 635, 222/209, 211–213, 215, 321.7–321.9, 372, 222/373, 378, 379, 383.1, 384–386, 398, 222/400.7, 400.8, 401, 402.1–402.25; 215/379, 215/382, 383, 384; 220/662, 665, 669, 674, 220/675

(57) **CLAIM**

The ornamental design for a dispenser, as shown and described.

DESCRIPTION

FIG. 1 is a perspective view of a dispenser showing the new design,

FIG. 2 is a left side elevation view of FIG. 1,

FIG. 3 is a right side elevation view of FIG. 1,

FIG. 4 is front elevation view of FIG. 1,

FIG. 5 is a rear elevation view of FIG. 1,

FIG. 6 is a top plan view of FIG. 1; and,

FIG. 7 is a bottom plan view of FIG. 1.

The appearance within the unshaded central region of FIG. 7 forms no part of the claimed design.

1 Claim, 4 Drawing Sheets
